UNITED STATES PATENT OFFICE

HARRY L. MAXFIELD AND WALLACE E. MIKKELSON, OF JANEVILLE, WISCONSIN

HYDROCARBON BURNER

Application filed March 8, 1928. Serial No. 260,079.

This invention provides an oil burner which is adapted to be manufactured economically, assembled with ease and dispatch, readily separable for any desired purpose and free from fastenings which corrode and prevent the easy dismemberment of the parts when, for any cause, it is desired to take the burner apart.

The invention supplies a burner which is capable of general use in furnaces, stoves and heaters, and which comprises a few number of parts which are accessible with the greatest facility for cleaning, replacement or other purpose.

15 While the drawing illustrates a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had 25 to the following description and the drawing hereto attached, in which,—

Figure 1 is a top plan view of an oil burner embodying the invention, one-half of the spreader being broken away to show the relation of the parts more clearly.

Figure 2 is a vertical, central sectional view of the burner.

Figure 3 is a perspective view of the annular deflector and oil catcher.

35 Corresponding and like parts are referred to in the following description and designated in the several views of the drawing by like reference characters.

The burner comprises a base which is 40 low and of circular outline. This base preferably consists of a casting and includes an outer wall 1, a top 2, an inner wall comprising inclined portions 3 and 4, and an inner flange 5 at the bottom edge of the inner wall.

45 The top portion 3 of the inner wall flares to effect a spreading of the flame. The bottom portion 4 of the inner wall tapers slightly. The annular deflector and oil catcher includes an outer wall 6 and an inner wall 7. These 50 walls 6 and 7 are oppositely inclined and en-

close a space which is of rounded outline at the bottom, as shown most clearly in Figure 2 of the drawing. A drain pipe 8 connects with an opening 9 formed in the bottom of the deflector to carry off surplus oil. The outer wall 6 is of greater height than the inner wall 7 and conforms to the taper of the portion 4 of the inner wall of the base, and upon the outer surface of the wall 6 are vertical ribs 10 engaging vertical grooves in the portion 4 whereby turning of the deflector and twisting of the pipe 8 is avoided.

The burner tip 11 consists of a plug provided upon its bottom side with lugs 12 which are stepped upon the bottom side to 65 provide inner and outer portions to properly center and support the tip. The outer portions of the lugs 12 rest upon the inner wall 7 of the annular deflector. The inner portions of the lugs 12 extend into the space 70 surrounded by the inner wall 7 and serve to properly position the tip. A vertical opening is formed centrally of the tip 11 and receives a pipe 13 which is threaded therein. The top side of the tip 11 slopes outwardly and downwardly in all directions, and is formed with a plurality of radially disposed grooves 14 which constitute passages for the flow of the gas. The grooves or passages 14 communicate with the upper end of the pipe 13. The 80 spreader 15 has its outer peripheral portion flared to conform to the flared portion 3 of the inner wall of the base. The annular space 16 formed between the flared portions of the spreader 15 and the base, constitute 85 a flame outlet which in the operation of the burner effects a spreading of the flame so as to reach the side walls of the fire box or like part in which the burner may be located.

A depression is formed centrally within the bottom side of the spreader 15 to snugly receive the burner tip 11. The space 17 formed between the adjacent walls of the burner tip and the recess of the spreader in which the burner tip is fitted flares downwardly and results in the formation of an annular outlet for the vapors flowing through the passages 14, thereby resulting in the production of an annular flame, which, after impinging upon the inner wall 7 of the annular deflector is 100

directed upwardly and outwardly through the flame outlet 16. Lugs 18 depend from the bottom side of the spreader 15 and are stepped similar to the lugs 12 to engage the outer wall 6 of the deflector and support and center the spreader. A lug 19 projects upwardly from the spreader and is disposed centrally thereof and is apertured to receive a suitable instrument for lifting the spreader 10 when required. A vaporizing or generating coil 20 is located within the space of the base and conforms to the bottom portion 4 of the inner wall thereof. The lower end of the coil 20 connects with the pipe 13 and the upper end connects with a supply pipe 21 leading from a tank, not shown, or other source of oil supply. This arrangement results in housing the coil 20 and preventing the chilling thereof when the burner is in 15 operation.

The burner is primed by supplying a small quantity of oil to the receptacle formed between the walls 6 and 7 of the annular deflector or oil catcher. Spaced webs 22 located 25 at the sides of the opening 9 prevent escape of the oil through said opening and drain pipe 8. The oil in the receptacle being ignited burns and heats the parts sufficiently to vaporize the oil flowing through the coil 30 20. The gas thus produced passes through the pipe 13 and ducts 14 to the outlet 17 where it is lighted, the resulting flame being deflected upwardly and outwardly through the space 16. The tops of the webs 22 are lower 35 than the top of the wall 7, and any oil accumulating in the catcher passes off through the outlet 9 and drain pipe 8 to the determinate point of discharge. It is observed that no fastenings are employed for connecting 40 the parts, hence the burner may be easily and quickly assembled and separated with the greatest facility, as occasion may require.

The burner tip 11 has a flange surrounding the opening formed therein in which the pipe 45 13 is fitted. The grooves 14 are formed in this flange. The surface exterior to the flange is unfinished to provide for a flow of the oil by preventing a close fit between the adjacent surfaces of the parts 11 and 15.

Having thus described the invention, we 50 claim:

1. A hydrocarbon burner including a hollow base and having the inner wall comprising an upper flared portion and a lower tapering portion, a vaporizing coil disposed within the space of the base and lying close to the lower tapering portion of the said inner wall, a burner supported within the lower tapered portion of the base, and a spreader 55 60 disposed above the burner and flared to conform to the flared portion of the base to form therewith a flared flame outlet.

2. A hydrocarbon burner comprising a hollow base including an inner wall having its 65 top portion flared and its bottom portion ta-

pered, an annular deflector and oil catcher supported within the lower tapered portion of the base and including inner and outer walls, a burner tip supported upon the inner wall of the deflector, and a spreader mounted 70 upon the outer wall of the deflector and fitting close against the burner tip, there being passages formed between adjacent sides of the tip and spreader which communicate with a flame outlet opposite the space formed between the inner and outer walls of the deflector. 75

3. A hydrocarbon burner comprising a hollow base including inner and outer walls, the inner wall having its upper portion flared, and its lower portion tapered, an annular deflector and oil catcher supported within the lower tapered portion of the inner wall of the base, a burner tip mounted upon the inner wall of the deflector, a spreader mounted 80 upon the outer wall of the deflector and having its outer side flared and spaced from the inner flared portion of the base, and a vaporizing coil within the base and disposed close against the tapered portion of the inner 85 wall thereof.

In testimony whereof we affix our signatures.
